(57) **CLAIM**

The ornamental design for a chair leg cover, as shown and described.

DESCRIPTION

FIG. 1 is a front perspective view of a chair leg cover, showing my new design;

FIG. 2 is a front elevational view thereof, the rear elevational view, the left side view and the right side view are identical; FIG. 3 is a top plan view thereof;

FIG. 4 is a sectional view of 4-4 along the line in FIG. 2; and, FIG. 5 is a sectional perspective view of 5-5 along the line in FIG. 2.

The broken lines in the figures are for the purposes of illustrating portions of the chair leg cover, which form no part of the claimed design.
